(57) **CLAIM**

The ornamental design for a mobile phone sheath embedded with projection device, as shown and described.

DESCRIPTION

FIG. 1 is a front, bottom and right perspective view of a mobile phone sheath embedded with projection device showing our new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof, the bottom view being a mirror image of FIG. 6.

The dot-dash broken line in FIG. 3 represents a boundary of the claimed design. The dash-dash broken lines depict environmental subject matter that forms no part of the claimed design. The broken lines and unshaded surfaces bounded by broken lines form no part of the claimed design.
